[57] CLAIM

I claim the ornamental design for a combined tobacco smoking pipe bowl and receiving stem, as shown and described.

DESCRIPTION

FIG. 1 is a perspective view of the combined tobacco smoking pipe bowl and receiving stem of my new design; FIG. 2 is a front exploded view thereof with the rear view being the same;

FIG. 3 is a top view thereof;

FIG. 4 is a bottom view thereof; and,

FIG. 5 is a view similar to FIG. 2 with the bowl and receiving stem interconnected in a use position.
